DESIGN FOR A FUNNEL

Herman H. Martin, Toledo, Ohio, assignor to
H. H. Martin Products Corporation, Toledo,
Ohio, a corporation of Ohio

Application March 20, 1939, Serial No. 83,702

Term of patent 14 years

To all whom it may concern:

Be it known that I, Herman H. Martin, a citizen of the United States, residing at Toledo, Lucas County, Ohio, have invented a new, original, and ornamental Design for a Funnel, of which the following is a specification, reference being had to the accompanying drawing, forming a part thereof, in which:

Figure 1 is an elevational view of a funnel showing my design, and

Figure 2 is a transverse sectional view taken substantially along the line 2—2 of Figure 1.

I claim:

The ornamental design for a funnel, substantially as shown.

HERMAN H. MARTIN.
